UNITED STATES PATENT OFFICE.

FLORENCE W. GOLDHAHN, OF PHILADELPHIA, PENNSYLVANIA.

FOLDING SCREEN.

1,282,685.

Specification of Letters Patent.

Patented Oct. 22, 1918.

Application filed July 20, 1918. Serial No. 245,873.

To all whom it may concern:

Be it known that I, FLORENCE W. GOLDHAHN, a citizen of the United States, residing at 8811 Lissner avenue, Philadelphia, in 5 the county of Philadelphia and State of Pennsylvania, have invented new and useful Improvements in Folding Screens, of which the following is a specification.

The invention relates to screens, and has 10 for an object to provide a screen that may be used for screening off or partitioning parts of a room, or in place of a door at an entrance, the screen being of a collapsible or foldable nature so as to form a compact 15 package when not in use whereby it can be readily stored away, and also providing for an adjustment whereby the screen by manipulation can be made to extend twice its length, if desired.

20 Among other features the invention comprehends a screen which is oftentimes known as a boudoir screen, and which may be arranged to partition off part of a room or an article of furniture, the screen being so 25 designed and constructed that it can be readily folded up and packed away in a small space when not in use. Further, the screen by reason of its novel design and construction can be manipulated to extend half of its normal 30 height when open, and twice its length or less, if desired. To this end the invention comprehends various novel forms of construction and arrangement, as will be hereinafter more fully described.

35 In the further disclosure of the invention, reference is to be had to the accompanying drawing, constituting a part of this specification, in which similar characters of reference denote corresponding parts in all 40 the views, and in which—

Figure 1 is a side elevation showing the screen at its full height and in open position.

Fig. 2 is a plan view.

45 Fig. 3 is a side elevation showing the screen reduced in height and made longer.

Fig. 4 is a view of the screen when folded, and

50 Fig. 5 is a fragmentary horizontal sectional view taken through a portion of the screen showing the construction.

Referring more particularly to the views, the screen in its entirety is designated by the numeral 10, and consists of a plurality of 55 sets of sections, the lower set of sections being indicated by the numeral 11, and the

upper set of sections by the numeral 12, with the first or main section of the lower set indicated by the numeral 13, and the remaining sections in the lower set by the numeral 14; the upper set having the first or main section indicated by the numeral 15, and the remaining sections in the upper set by the numeral 16. Each section consists of a rectangular frame, comprising a bottom 60 17, a top piece 18 and sides 19, which are suitably connected to form a rectangular or square frame, and each of the sections are then covered with a suitable material indicated by the numeral 20. This material 65 may be cloth, wood paneling or any other form of construction desired. The main lower section 13 has the next adjacent section 14 hinged thereto by means of suitable 70 hinges 21, similar hinges being employed 75 to hinge the remaining sections 14 adjacent each other, together, it being of course understood that whereas the hinges connecting the first two sections in the lower set are to one side, the pair of hinges connecting 80 one of said sections with the next adjacent section would be on the opposite side and so on, alternating throughout the entire set of sections. So also the first upper section 16 is hinged by means of suitable hinges to the 85 main upper section 15, and the remaining upper sections 16 are hinged to each other as described heretofore in the arrangement of the lower set of sections. When the sets of sections are arranged as shown in Fig. 1, it 90 will be seen that the main upper section 15 will repose upon the main lower section 13, and the next section 16 will repose upon the next lower section 14 and so on. In order to prevent the screen from collapsing, suitable 95 catches 22 are arranged to connect the superposed sections and hold them against accidental removal, the disengagement of the catches permitting of removing the upper set of sections from the lower set of sections. 100

It will be seen that the first upper section 15 is also hinged by hinges 23 similar to the hinges 21, to the first or main lower section 13, by having the hinges attached to the bottom of the first upper section and the top of the first lower section 13. With this construction, when the catches are unfastened to disengage the superposed sections in the upper and lower sets, the entire upper set can be swung upon the hinges which are attached to the first section 13 so as to reduce the height of the screen one-half, and this 105 110

will bring the main upper section adjacent to the first main lower section, as shown in Fig. 3, thus permitting of opening up the remaining upper sections 16 so that they will 5 extend adjacent to and in the horizontal line of the lower set of sections, thereby enlarging the screen as to its length. With this construction the screen when in its normal set-up position can be arranged so that it 10 will extend upwardly only half its height but twice as long or less, as desired, it being of course understood that one of the upper sections when the screen is swung downwardly, can be folded upon another section 15 now in a lowered position, so as to reduce the length of the screen.

With the arrangement set forth in Fig. 3, it will be apparent that the auxiliary lower sections in the lower set will extend to 20 one side of the main section in the lower set, and the auxiliary upper sections in the upper set will extend to one side of the main section in the upper set, which now lies adjacent to the main section in the lower set, 25 and with this construction the device can be adapted for various purposes, as for instance, inclosing an article of furniture in a room, or to form a longer partition as the case may be. Whether the device is in the 30 reduced extended position, or in its vertically enlarged position, it will be apparent that the sections can be readily collapsed one upon the other and the entire device form a compact package, so that it can be 35 stored away without taking up a great deal of room when it is not desired to use the screen, and it will be apparent that by having a screen of the character mentioned, the one construction adapted for various 40 purposes will serve in place of two individual screens, which might ordinarily have to

be used in a case where a person desires a screen at one time of a certain height, and at a later time a screen, shorter or longer in length. 45

I claim:

1. A folding screen comprising a plurality of sets or sections forming a lower set and an upper set, each of said sets including a main section and auxiliary sections and having one of the auxiliary sections hinged thereto and the remaining auxiliary sections alternately hinged to each other, said main section in the lower set being hinged to the main section in the upper set, to permit of 50 swinging the upper set from normal superposed position on the lower set, downwardly into a position to extend in opposite directions to the sections in the lower set, with the two main sections lying in adjacent relation. 60

2. A folding screen comprising a plurality of sets of sections forming a lower set and an upper set, each of said sets including a main section and auxiliary sections and having one of the auxiliary sections hinged 65 thereto and the remaining auxiliary sections alternately hinged to each other, said main section in the lower set being hinged to the main section in the upper set, to permit of swinging the upper set from normal superposed position on the lower set, downwardly into a position to extend in opposite directions to the sections in the lower set, with the two main sections lying in adjacent relation and catches for holding the sections in the 70 lower set to the sections in the upper set against relative movement when the sections in the upper set are superposed upon the sections in the lower set. 75

In testimony whereof I affix my signature. 80

FLORENCE W. GOLDHAHN.
